UNITED STATES PATENT OFFICE.

MINARD A. POSSONS, OF CLEVELAND, OHIO, ASSIGNOR TO AMERICAN STOVE COMPANY, OF ST. LOUIS, MISSOURI, A CORPORATION OF NEW JERSEY.

OVEN DOOR.

Application filed April 12, 1926. Serial No. 101,565.

This invention relates to improvements in oven doors and has in view the general idea of a spring closed door of special construction which will be specified hereinafter.

5 The primary object of this invention is to make a hingeless spring closed door.

Another object of the invention is to so construct the spring and other parts that when the door is opened to a horizontal position it will remain in that position but when lifted it will snap closed with considerable force, thus making a tight closure.

Another object of the invention is to so construct a brace that is attached to the door 15 and to which the spring is connected that it acts as a positive stop to hold the door in a horizontal position and to sustain that position for supporting articles placed thereon.

Another object of the present invention is 20 to provide a spring so constructed that it rests in a vertical plane in the oven between the lining and the wall of the oven, whereby the lining does not interfere or strike the said spring.

25 A further object of the present invention is to locate the brace for the spring between the lining and the door whereby the brace acts as a stiffening device for the door and to hold it against being twisted out of shape.

30 Additional objects of the invention will appear from the following description:

Figure 1 is a vertical central sectional view through the front part of an oven showing my improved door applied thereto.

35 Figure 2 is an inside plan view of an oven door showing my improved spring brace applied thereto.

Figure 3 is a sectional view on the line 3—3 of Figure 2 showing part of the attachment of the brace to the lining of the door.

40 Figure 4 is a sectional view of Figure 2 on the line 4—4, showing the means for attaching the lining, the brace and the handle to the door.

45 Figure 5 is a detached perspective view of one of my improved brace bars.

Figure 6 is a perspective view looking at it from the opposite side from that shown in Figure 5.

50 Figure 7 is a detached perspective view of my improved spring.

Figure 8 is a detail view of the loop at the inner side of the oven that receives one end of the spring.

Figure 9 is a sectional view showing the 55 door in its horizontal position.

Figure 10 is a detached perspective view of the lower ends of the spring and the brace rod.

Figure 11 is a front view of the lower end 60 of the door opening of the oven.

Figure 12 is a horizontal sectional view showing an oven wall, a lining therefor and the spring and door arm located between the 65 lining and the oven wall.

Figure 13 is a vertical central perspective view taken through the lower edge of the door structure.

The present invention is adapted to be applied to ovens having various constructions, 70 and to doors that are differently constructed. For the purpose of illustrating the present improvement, I have shown the door applied to a conventional oven structure and have also shown the door of a conventional 75 construction. These features, however, may be varied without departing from the spirit and scope of the present invention.

Figure 1 is a vertical section showing the front wall 1 of an oven to which the door 2 80 is applied.

In the form of oven door here shown, it comprises an outer panel 3 that has its edge 4 turned inward, and a door lining 5 with its upper edge 6 located within and telescoping 85 the flange 4 of the outer panel 2. Applied to the door and as here shown located between the lining and the outer panel, is a brace bar 7. This brace bar comprises a vertical leg portion 8 and an upwardly inclined 90 leg portion 9. The lower end of this brace has an inwardly extending curved arm 10, which is arranged to extend at right angles to the remaining portion of the brace bar. This curved portion 10 passes loosely 95 through an opening 11, the said opening being considerably larger than the arm 10.

Thus far the door is an element that is entirely separate and disconnected in any manner from the oven 1. It may be removed 100 from the oven since it is wholly disconnected therefrom.

When the door is to be connected with the oven, the curved arm 10 is passed through the opening 11, and to the extremity 12 of 105 the arm is attached a spring 13. The upper end 14 of the spring passes through a suitable loop 15 that is attached to the inner side

of the outer wall 16 of the door opening. This loop may be welded or otherwise attached to the wall.

The spring consists of a heavy wire that 5 is made of spring material. Intermediate its ends the spring is formed into a circle or loop 17, its upper arm 18 projecting forward and having its end 14 passing through the loop 15 as above stated. The opposite and 10 lower arm 19 of the spring has its end 20 turned laterally preferably outwardly, whereby the spring lies between the extremity of the arm 10 and the wall 21 of the oven. The end 14 is laterally bent upward and 15 passes through the loop 15 while the end 20 is bent horizontally and passes through the opening 22. From the foregoing it will be observed that my spring comprises essentially the two described arm portions and a 20 circle or loop 17. This spring is arranged so that the arms 18 and 19 normally separate, that is to say the arm 18 normally moves upward and the arm 19 normally moves downward. This action places a pull on the 25 curved arm 10 that acts to close the door 2.

Attention is directed to the fact that the lower end 23 of the door as here shown, is made substantially horizontal, and this rests on a horizontal portion 24. Therefore when 30 the door is opened it turns on the angular portions 23 and 24, the said arm 10 being made on a circle that has its axis substantially on that part of the lower edge of the door that engages the parts 24 and 25 of 35 the stove structure.

From the foregoing it will be observed that the door is not provided with a hinge of any kind as is ordinarily the case and the arm 10 normally travels freely through the 40 opening 11. The spring acts to hold the lower end of the door when in a vertical position in engagement with the part 24 and when it is being opened, the lower end is held in the angle between the part 24 and 26. 45 Preferably these engaging parts are only at the ends of the door, whereby the construction is practically unnoticeable.

The spring, therefore, acts to hold the door firmly in its proper position, whether it is 50 closed, and in its various positions in being opened, and in its horizontal position. The arms 19 and 18 serve to exert a downward pull on the extremity of the arm 10 and the end 14 being held against endwise movement by the loop 15, the door is held against any outward movement. In fact in an actual construction such as that herein shown and described, the door being partially open, it is difficult to lift it from its position on the 55 oven frame. When the door is in a horizontal position, then the extremity of the arm 10 lies substantially closed to a pull that is substantially in a line with the turning fulcrum or part of the door and hence when 60 the door is horizontal, it remains in that

position, but when it is lifted a short distance and released, it will snap closed very quickly and is held quite firmly.

For the purpose of sustaining the door in its horizontal position, I provide the inner 70 side of the arm 10 with an inwardly projecting stop arm 26 that strikes the oven wall 16 when the door reaches the said position.

For the purpose of adding strength to the 75 door, the leg 8 of the brace extends upward a considerable distance and is attached to the lining by a screw 27 that passes in an opening 28 in the lining and into a suitable screw nut 29 that is at the outer side of the 80 brace. The lower end 30 of the brace is also secured to the lining 5 by means of a screw that passes through an opening 30 in the lining and held in the same manner as the screw 27. The extremity of the leg 9 of the 85 brace 7 is held by the same screw 32 that serves to unite the handle 33 to the door 2. The screw passes through an opening 34 formed in the extremity of the leg 9 and into a screw 90 threaded opening 35 formed in the stem portion of the handle 33.

Attention is directed to the fact that the inner and lower end 25 of the door is turned upward as at 36 and laps over the adjacent 95 lower edge of the lining 5.

From the foregoing description it will be understood that the brace rod 7 is secured by a bolt that passes through the lining, the outer door panel 5 and into the handle 33. 100 It will also be understood that in order to disconnect the outer door panel 2 from the lining 5 and the brace rod, it is only necessary to loosen the screws 34 when the outer door panel can be removed for any purpose 105 whatever, such for instance, as enameling or otherwise. This construction also enables the lining 5 to have the brace rods 7 attached thereto and afterwards the door attached to the lining before or after the 110 lining is attached to the oven.

The brace rods 7 are made right and left, owing to the fact that the leg 9 extends inward and the arm 10 extends at right angles to the vertical leg 8.

For the purpose of holding the end 20 of the arm 19 of the spring 13 from being accidentally removed from its opening 22, its end 20 is slightly curved down whereby its curved extension 20' when applied to the arm 10 is located inside of the arm 10, thus serving to hold this end in position in its opening as shown in Figure 10.

The corners of the lower end of the wall 16 that forms the door opening constitute 125 turning points for the door which are narrow as shown at 37.

I wish it understood that variations in the construction herein shown and described may be made without departing from the scope 130

and spirit of the present invention so long as any changes are fairly within the scope of the appended claims.

Having thus described my invention, what I desire to claim and secure by Letters Patent is:

- 5 1. The combination of a door frame having a door seat with an open outer end at one side thereof, a door normally resting loosely on said seat, and an elongated substantially U-shaped normally expanding spring having one end supported independently of said door and its opposite end attached to the door near its seat, said spring 10 pulling inward and pressing down on the said door, whereby it acts as described.
- 15 2. The combination of a door frame having at its bottom a door seat with an open outer end located at its outer side, a door having its lower edge normally resting loosely 20 on the said seat, and a horizontally elongated substantially U-shaped normally expanding spring extending inward, the upper end of the spring connected with the said door frame and its lower end attached to the door near its side, said spring acting to pull 25 inward and downward whereby the door is firmly held on its seat in its various positions.
- 30 3. The combination of a door frame having a door opening with an external door seat with an open outer end at its lower portion, a door normally resting loosely on said seat, and a horizontally elongated substantially U-shaped normally expanding spring having one end fixed to the said door frame and its opposite end attached to the door 35 near said seat, the said spring pulling inward and downward on the door whereby it is firmly held to the seat as it is moved to its various positions.
- 40 4. The combination of a door frame having a door opening, the lower wall of the said opening having a door seat with an open outer end, a door normally resting loosely on said seat, and two essentially U-shaped normally expanding springs located at opposite sides of the said opening, said springs extending inward, the upper ends of the said springs fixed to the said frame and the lower ends of the said springs attached to the door near the said seat, the springs pulling inward and pressing downward on the said door whereby the door is firmly held 50 to its seat as it is moved from closed to open positions.
- 55 5. An oven comprising side walls and inner linings spaced from the side walls, the front of the oven having a frame provided with a door opening, the lower wall of the said opening having a door seat with an open outer end, a door normally resting loosely in the said seat, essentially a U-shaped normally expanding spring located in the said space between the lining and the wall of the

oven, the U-shaped expanding spring elongated horizontally and extending vertically, the upper end of the U extending outward and attached to the said frame, the opposite end of the U connected with the door adjacent its said seat, the spring acting to constantly pull inward and press downward on the said door whereby the door is constantly held to the seat as it is moved to open or closed positions.

6. The combination of a door frame having at its lower portion a door seat with an open outer end externally arranged, a door normally resting loosely in the said seat, the door having an inwardly extending arm at its lower part, said arm passing wholly freely inward, and an inwardly elongated essentially U-shaped normally expanding spring located in a vertical position, the upper end of the spring fixed to the said frame and the lower end of the spring attached to the inner end of said arm, the spring acting to constantly pull inward and press downward on the said arm, whereby the door is constantly held firmly to its seat as it is moved from open to closed positions.

7. An oven construction comprising a front wall having a door opening with a door seat with an open outer end located at its lower portion, a door normally resting loosely in the said seat, a brace rod extending upward substantially throughout the height of the said door, said brace rod having an arm extending inward at right angles to the said bar, a horizontally elongated essentially U-shaped normally expanding spring located inside the walls of the said oven, said spring arranged substantially in a vertical position, the upper end of the spring fixed to the said door frame and its lower end attached to the inner end of the said arm, whereby the door is braced and held constantly to its seat as it is moved to open or closed positions.

8. An oven having a front wall provided with a door opening, the lower end of the opening having substantially an L-shaped door seat, a door having one edge resting in the said seat and also having substantially a right angle portion engaging the said L-shaped portion, and an expanding spring within the walls of the oven, said spring being essentially U-shaped, the upper end of the spring attached to the door frame and its lower end attached to the door near its angular end, the spring acting to constantly exert a downward and inward pull on the said door, whereby when opening the door said angular portions act to hold the door closed and when the door reaches its horizontal position to hold the door open as described.

In testimony whereof I hereunto affix my signature.

MINARD A. POSSONS.
